UNITED STATES PATENT OFFICE.

REME A. BEAUSEJOUR, OF NEW YORK, N. Y., ASSIGNOR TO STANDARD VARNISH WORKS, OF NEW YORK, N. Y., A CORPORATION OF NEW YORK.

ARTICLE-HOLDER FOR LIQUID-COATING MACHINES.

1,072,810.

Specification of Letters Patent.

Patented Sept. 9, 1913.

Application filed December 27, 1909. Serial No. 534,968.

To all whom it may concern:

Be it known that I, REME A. BEAUSEJOUR, a subject of the Crown of Great Britain, and resident of the borough of Brooklyn, in the city and State of New York, have invented a new and useful Article-Holder for Liquid-Coating Machines, of which the following is a specification.

This invention relates to article holders used in connection with machines for dipping articles for the purpose of coating them with some sort of a liquid, such as varnish; its general object being to provide a structure which will permit the articles being dipped to acquire a coating of the liquid of a perfectly even thickness on all parts of the said article.

More specifically, the invention provides means for reversing the position of the articles to be coated while the varnish or other liquid is dripping from the articles and while the articles are drying, in order to vary the direction of flow of the dripping liquid and thus prevent it from collecting 25 on any one edge or part of the article.

Another object is to provide means for rotatably adjusting the part which supports the articles to be coated, in order that all the articles in the holder may be reversed 30 at once.

A further object is to provide article holding clamps which are longitudinally and rotatably adjustable on the part which supports the articles to be coated, whereby 35 the articles may be held in any desired position on the said part.

A still further object is to provide an improved form of article holding clamp which will insure a positive holding of the article 40 to be coated and yet not come in contact with the said article on any of the surfaces which are to be exposed when the article is put to its final use.

A still further object is to provide certain improvements in the form, construction and arrangement of the various parts, whereby the above named objects may be carried out.

A practical embodiment of the invention 50 is represented in the accompanying drawings in which,

Figure 1 represents an end view of the article holder, showing the articles in one position in full lines and in their reversed 55 position in dotted lines. Fig. 2 represents

a detail side view of the parts shown in Fig. 1. Fig. 3 represents a detail top plan view of the same. Fig. 4 represents a section taken in the plane of the line A—A of Fig. 1, looking in the direction of the arrows. Fig. 5 represents a side elevation of the article holding clamp. Fig. 6 represents a rear elevation of the same. Fig. 7 represents an end view of a modified form of article holder, showing the article supported therein. Fig. 8 represents a detail side view of the same. Fig. 9 represents a detail top plan view of the same. Fig. 10 represents a detail view of one of the combined cross-frames and article holding 60 clamps of the modified form represented in Figs. 7 to 9, and Fig. 11 represents a section taken in the plane of the line B—B of Fig. 10, looking in the direction of the arrows.

Referring to Figs. 1 to 6 inclusive, the frame of the article holder comprises the side members 1 and top member 2, and is pivotally supported, as at 3, from carriages 4 mounted in a horizontal support 5. The 65 particular structure of the parts 2, 3, 4, 5, is not a part of this invention, and hence they will not be described in detail. The articles to be coated are indicated by 1*. A shaft 6 is journaled in the side members 70 80 85 90 95 100 105 110 115 120 125 130 135 140 145 150 155 160 165 170 175 180 185 190 195 200 205 210 215 220 225 230 235 240 245 250 255 260 265 270 Referring now to the form shown in Figs. 7 to 11 inclusive, the frame comprises the side members 20 and top member 21 which are supported in a manner similar to that in connection with the form shown in Figs. 1 to 4 inclusive. The articles to be dipped are indicated by 20*. A rod 22 is journaled in the side members 20, and on this rod are slidably mounted a series of combined cross-frames and article holding clamps 23. These cross-frames 23 are provided with a longitudinal series of holes fitted to receive rods 24 for holding the parts 23 in substantially the same plane, whereby the parts 23 may suitably support the articles 20* in the holder. Pins 25 are provided for holding the rods 22, 24, against accidental displacement from the side members 20 and combined cross-frames and article holding clamps 23. These parts 23 are provided with a series of spikes 26 and wood screws 27. The wood screws have enlarged heads 28 for their convenient manual operation. One of the combined cross frames and article holding clamps 23 is provided with a sleeve 23* to which is secured a double handle 29 for moving it to a desired rotative adjustment. Each end of this handle 29 is provided with a hole 30 which registers with a hole 31 in a side member 20, and a pin 32 is provided for securing the handle 29 in position with either one of its holes 30 in register with the hole 31.

In operation, referring now to all the figures, the wood screws 16, 27, are withdrawn so as not to leave either points projecting beyond the surface of the article holding clamps. The articles to be coated, such as parts of a piano casing, are then forced 40 against the clamps so as to embed the spikes 14, 26, in the said article. Care is taken to embed these spikes in some portion of the article which will not be visible when the article is put to its final use. The wood screws 16, 27, are now screwed into the article to be dipped care being taken that these screws shall not enter any portion of the article which is to be finally exposed, and the article is then firmly held by the clamp. 45

In the case of the structure shown in Figs. 1 to 6 inclusive, the clamps with the article may be secured in any desired adjustment on the shaft 6 by means of the set screws 19; but in the structure represented in Figs. 50 7 to 11 inclusive, the combined cross-frames and clamps 23 cannot be rotatably adjusted on the shafts 24. The shaft 6 and the combined cross-frame and clamp 23 may be moved to the desired rotative adjustment by 55 the handles 8 and 29, and secured in said adjustment as described above. After the articles have been dipped, their position in the frame may be reversed as desired, by turning the handles 8 and 30 to the other 60 angular adjustment and securing them 65

therein as formerly. Thus the liquid with which the articles have been coated may be allowed to drip for a while from one corner of the articles and then for a while from another corner. This will avoid the collection of a considerable amount of the liquid at one corner of the article, and consequently insure an even coating throughout the entire article. 70

It will be seen that the clamps herein described are particularly well adapted for holding parts of a box-like casing, such as a piano casing, in which one side and one or more edges of each part are hidden from view when the entire casing is assembled, 80 for the reason that the spikes and screws may get a firm grip on the article itself without in any way marring its appearance when finally in its assembled position. 85

It will be seen that I provide means for reversing the angular position of the articles being coated, which is very simple and which may be very conveniently and expeditiously operated; the whole set of articles held in the holder being reversed with one 90 movement. 95

It is plain that various changes may be resorted to in the form, construction and arrangement of the different parts of this apparatus, without departing from the spirit and scope of my invention; hence I do not wish to limit myself strictly to the form herein shown and described, but 100

What I claim is:

1. An article holder for liquid coating machines comprising mechanism for supporting the articles being coated, and a clamp carried by said mechanism for holding the articles thereon, said clamp being rotatably adjustable on said mechanism. 105

2. An article holder for liquid coating machines comprising mechanism for supporting the articles being coated, and a plurality of clamps carried by said mechanism for holding the articles thereon, said clamps being rotatably adjustable on said mechanism. 110

3. An article holder for liquid coating machines comprising mechanism for supporting the articles being coated, a clamp carried by said mechanism for holding the articles thereon, said clamp being longitudinally and rotatably movable on said mechanism, and means for securing said clamp in different longitudinal and angular positions on said mechanism. 115

4. An article holder for liquid coating machines comprising mechanism for supporting the articles being coated, a plurality of clamps carried by said mechanism for holding the articles thereon, said clamps being longitudinally and rotatably movable on said mechanism, and means for securing said clamps in different longitudinal and angular positions on said mechanism. 125

5. An article holder for liquid coating machines comprising mechanism for supporting the articles being coated, a clamp carried by said mechanism for holding the articles thereon, said clamp being longitudinally and rotatably movable on said mechanism, and means for securing said clamp in any different longitudinal and angular positions on said mechanism.
- 10 6. An article holder for liquid coating machines comprising mechanism for supporting the articles being coated, a plurality of clamps carried by said mechanism for holding the articles thereon, said clamps being longitudinally and rotatably movable on said mechanism, and means for securing said clamps in any different longitudinal and angular positions on said mechanism.
- 15 7. An article holder for liquid coating machines comprising a frame, a shaft mounted to move in a rotary direction therein, a device for moving said shaft to different rotative positions, a device for locking said shaft in different rotative positions, and an article holding clamp adjustable longitudinally and rotatably on said shaft.
- 20 8. An article holder for liquid coating machines comprising a frame, a shaft mounted to move in a rotary direction therein, a device for moving said shaft to different rotative positions, a device for locking said shaft in different rotative positions, and a plurality of article holding clamps mounted on said shaft and arranged to be locked in different longitudinal and rotative ad-
- 25 justments.
- 30 9. An article holder for liquid coating machines comprising a frame, a shaft mounted to move in a rotary direction therein, a device for moving said shaft into different rotative positions, a device for locking said shaft in different rotative positions, and an article holding clamp mounted on said shaft and arranged to be locked in different longitudinal and rotative ad-

locking said shaft to different rotative positions and a plurality of article holding clamps adjustable longitudinally and rotatably on said shaft.

35 10. An article holder for liquid coating machines comprising a frame, a shaft mounted to move in a rotary direction therein, a device for moving said shaft into different rotative positions, a device for locking said shaft in different rotative positions, and an article holding clamp mounted on said shaft and arranged to be locked in different longitudinal and rotative ad-

40 justments.

45 11. An article holder for liquid coating machines comprising a frame, a shaft mounted to move in a rotary direction therein, a device for moving said shaft into different rotative positions, a device for locking said shaft in different rotative positions, and a plurality of article holding clamps mounted on said shaft and arranged to be locked in different longitudinal and rotative ad-

50 justments.

55 In testimony, that I claim the foregoing as my invention, I have signed my name in presence of two witnesses, this twenty second day of December 1909.

REME A. BEAUSEJOUR.
